DESIGN FOR A SEWING MACHINE CASING

John P. Weis, Nyack, N. Y.

Application December 14, 1935, Serial No. 60,082

Term of patent 14 years

To all whom it may concern:

Be it known that I, John P. Weis, a citizen of the United States, residing at Nyack, in the county of Rockland and State of New York, have invented a new, original, and ornamental Design for a Sewing Machine Casing, of which the following is a specification, reference being had to the accompanying drawing, forming a part thereof, and in which:—

Figure 1 is a top plan view of the sewing machine casing showing my design.

Figure 2 is a front view of the sewing machine casing shown in Fig. 1.

Figure 3 is a side view of the sewing machine casing.

Figure 4 is a perspective view.

I claim:

The ornamental design for a sewing machine casing substantially as shown.

JOHN P. WEIS.
